MONEY CLASP

Robert C. Haltom, Fort Worth, Tex.

Application July 27, 1950, Serial No. 11,433

Term of patent 14 years

(Cl. D17—10)

To all whom it may concern:

Be it known that I, Robert C. Haltom, a citizen of the United States, residing at Fort Worth, State of Texas, have invented a new, original, and ornamental design for a Money Clasp, of which the following is a specification, reference being had to the accompanying drawing, forming a part thereof.

Figure 1 is a top plan view of a money clasp showing my new design;

Figure 2 is a view in side elevation;

Figure 3 is a bottom view;

Figure 4 is a view from one end; and

Figure 5 is a view from the opposite end.

I claim:

The ornamental design for a money clasp, as shown.

ROBERT C. HALTOM,
